R. C. EDWARDS

RELEASING DEVICE FOR LIFEBOATS AND OTHER SIMILAR CRAFT

Filed May 5, 1919

INVENTOR.

Richard Corey Edwards:

BY

E. Miles

ATTORNEY.

UNITED STATES PATENT OFFICE.

RICHARD COREY EDWARDS, OF OAKLAND, CALIFORNIA.

RELEASING DEVICE FOR LIFEBOATS AND OTHER SIMILAR CRAFT.

Application filed May 5, 1919. Serial No. 294,894.

To all whom it may concern:

Be it known that I, RICHARD COREY EDWARDS, a citizen of the United States, and a resident of the city of Oakland, in the county of Alameda and State of California (whose post-office address is No. 1311 One hundred and seventh Avenue), have invented a new and useful Releasing Device for Lifeboats and Other Similar Craft, of

10 which the following is a specification.

My invention relates to a device for the easy and safe handling of life boats and other similar craft, when being lowered and put into use from larger vessels, in which 15 twin hooks are mounted in a frame and are attached by brackets on the inside of the fore and after part of the boat; the mechanism of the two hooks are connected by a shaft made of iron pipe of suitable size 20 which extends fore and aft along the bottom of the boat; the said shaft is provided with a folding handle, by means of which it may be rotated, and when not in use the handle may be folded down along the side of the 25 shaft. The shaft is securely anchored to the bottom of the boat by suitable bearings in which it may be rotated, and at the outer ends of the said shaft are two cranks or eccentrics which are rigidly attached to the 30 said shaft. The hooks are provided with elongated shanks, and near the middle of each of the said shanks, there is a hole, by means of which the said hooks are mounted on a bolt extending through the said frames. 35 The shank of each of the said hooks extends downwardly from the said bolt and forms a lever. The said bolt constitutes a fulcrum on which the said hooks are rotated for opening and closing the same. Within the said 40 frames, and in alignment with the lower part of each of the said levers, is a trigger mounted on a fulcrum within the said frame. The lower end of the said triggers extend below the bottoms of the respective frames, 45 and are connected by suitable fastenings to rods by means of which they are operated. The front end of each of the said triggers when the hooks are closed, rests against the inside face of the said levers. The trigger 50 rods, to which the triggers are attached at their lower ends, are in two parts; the upper portion being formed of iron pipe, flattened at the end which is attached to the

trigger and provided with a hole in which a bolt is inserted, but having a channel in its lower portion. The lower end of the respective trigger rods are of solid metal, and are flattened at their lower ends and each are provided with a hole by means of which they are movably attached to the crank or eccentric at each end of the said shaft. The lower portion of the said trigger rods are somewhat smaller than the upper portions, and are designed to penetrate the channel in the said upper portion, until the bottom of the upper portion comes into contact with the shoulder on the lower portion; this contact is made and the trigger actuated, by rotating the said shaft by means of the folding handle. The trigger rods attached to the eccentric at each end of the said shaft, raise the lower ends of the triggers simultaneously and the front ends of the said triggers are forced downwardly below the points of the said levers, when the hooks are simultaneously released by the weight of the boat on them. The front ends of the said triggers are each beveled so that the pressure exerted on them by the levers of the respective hooks causes them to rise so that the lower portions of the said triggers are at all times pressed firmly against the stop pin shown in the drawing, thus making accidental release impossible.

The object of my invention is the saving of human life by providing a better and safer method of launching life boats during storms or accident at sea.

Another object of my invention is to provide a means of releasing life boats and other small craft from their tackle by perfectly synchronous action, thus preventing the many disasters due to releasing one end of the boat at a time, and throwing its burden into the sea.

A still further object of my invention is to provide a means whereby a life boat or other small craft may be easily and quickly released from its tackle by one person.

I attain these objects by the mechanism illustrated in the accompanying drawing, in which:

Fig. 1 is a section of boat showing side elevation of my device in place as it hangs in the tackle.

Fig. 2 is a side elevation of an enlarged

view, with parts broken away to show the position of the hook and trigger.

Fig. 3 is an end view of the hook detail, showing the release trigger in two parts with the operating rod attached thereto.

Similar figures refer to similar parts throughout the several views.

One (1) is the keel of the boat; 2—2 are the ropes of the tackle suspending the boat; 10 3—3 are the eyes in the ends of the ropes that engage with the hooks; 4—4 are the hooks that engage with the eyes; 4^a—4^a are levers, made integrally with the said hooks, by means of which they are firmly locked when 15 closed; 5—5 are the frames in which the hooks and triggers are mounted. These frames are preferably made from one piece of iron pressed into proper form and having its edges firmly bound together by clamps 20 12—12; 6—6 are bolts passing through the sides of the said frames and on which the said hooks are mounted; and forms the fulcrum between the hooks 4—4 and the levers 4^a—4^a; 10—10 are brackets, having two lugs 25 8—8 and 9—9 formed integrally therewith, and having a suitable number of holes in their outer faces by which they are firmly attached by bolts to the framework of the boat, (see 11—11); the frames 5—5 are disposed between the lugs 8—9 and are held in place by bolts 7—7; 14—14 are triggers which are mounted on fulcrum 15—15 so that when the hooks are closed and the triggers are in place, the face of the levers 30 4^a—4^a rest against the upper ends of the said triggers; 16—16 are joints connecting the lower ends of the said triggers with operating rods 18—18; 17—17 are stay pins which pass through both sides of the said frames and beneath the said triggers and prevent them from slipping out of place. I prefer to manufacture these triggers in two parallel sections, as experience has shown that a double trigger will release much easier than one made of a single piece. The trigger release rods 18—18 and 19—19, are made in two sections the lower portion telescoping into the upper portion, so that either one or both may be locked or unlocked without operating the entire mechanism; 20—20 are the flattened portions of the lower sections of the trigger release rods and are movably connected to cranks 21—21 by bolts in the manner shown; 23 is a shaft which extends 35 longitudinally with and in close proximity to the bottom of the boat from stem to stern and has a channel throughout its entire length. At each of its ends, a crank 21 is rigidly attached by means of a shank which is inserted and firmly riveted in the ends of the said shaft. 22—22 are bearings which are suitably fastened to the bottom of the said boat, and support and hold the said shaft in place; 24 is a handle which may be 40 made of any suitable material, preferably 55 60 65 70 75 80 85 90 95 100 105 110 115 120 125 130

iron, and is attached by means of a clamp to the said shaft as shown; the said handle is attached to the said clamp by means of a bolt in hole 25, in such way that it may be folded out of the way and is held by spring clamp 28 which is attached to said shaft. No claim is made however, for patent on the handle as here shown.

Having now fully described my invention, that which I claim to be new and desire to secure by Letters Patent is:

1. A releasing device for life boats, to be used in duplicate, of the kind described, comprising frames made integrally and pivotally attached to the hull of the said boat, at the ends thereof, a hook mounted on a fulcrum within each of the said frames, the said hooks each having an elongated shank and forming a lever below the said fulcrum, the faces of the said shanks being straight and mounted at right angles with respect to the triggers, when the hooks are closed; a trigger of two parallel sections mounted on a fulcrum within each of the said frames so that the front ends of the said triggers may be brought in contact with the said levers when the hooks are closed, the front ends of the said triggers at the point of contact with the said levers, being beveled downwardly; a shaft rotatably disposed in the said boat and extending along the keel thereof, a crank rigidly affixed to each end of the said shaft, an operating lever mounted on the said shaft and relatively movable telescoping releasing rods connecting the cranks and the triggers, the said cranks being so attached to the said shaft that the hooks if closed when the operating lever is in a horizontal position, will be locked.

2. In combination, a releasing device for boats and other similar craft, to be used in duplicate, comprising frames made integrally and suitably attached to the hull of the said boat at the ends thereof, a fulcrum within each of the said frames, a hook disposed upon each of the said fulcrums having an elongated shank, holes through the said shanks near the middle by which the said hooks are rotatably mounted on the said fulcrums within the said frames, the lower ends of the said shanks extending below the said fulcrums so as to form levers, triggers of two parallel sections mounted on a fulcrum within each of said frames so that its front end is in contact with the said lever when the hooks are closed; the faces of the said levers which come in contact with the front ends of the said triggers being straight, and the front ends of the said triggers being beveled so that the pressure of the said levers will cause the same to move upwards and be held firmly against the stay pins; a stay pin within each of the said frames to engage with the lower portion of the said trigger; a hollow shaft, rotatably

disposed longitudinally along the keel of the said boat between the said devices, an eccentric rigidly affixed to each end of the said shaft with its upper portions movably attached to the lower end of the respective trigger, and the lower end of the same movably attached to the said eccentric, and an

operating handle suitably affixed to the said shaft; the said eccentrics being so attached to the said shaft that when the operating handle is in a horizontal position the hooks if closed are locked; all substantially as described and set forth. 10

RICHARD COREY EDWARDS.
